UNITED STATES PATENT OFFICE.

LAZARD KAHN AND ADAM SPECK, OF HAMILTON, OHIO, ASSIGNORS TO
F. & L. KAHN & BROS., OF SAME PLACE.

DESIGN FOR A HEATING-STOVE.

SPECIFICATION forming part of Design No. 24,016, dated February 5, 1895.

Application filed October 31, 1894. Serial No. 527,577. Term of patent 14 years.

To all whom it may concern:

Be it known that we, LAZARD KAHN and ADAM SPECK, citizens of the United States, residing at Hamilton, Butler county, Ohio, have 5 invented and produced a new and original Design for a Heating-Stove, of which the following is a specification.

Our design for a heating stove is fully shown in the accompanying drawing, which 10 represents a perspective view of the stove.

In our design the stove is a vertical column substantially rectangular in horizontal cross-section, but the sides, between the vertical corners, are swelled outwardly as shown. The 15 structure is surrounded by three bands, A, B, and C, and is surmounted by a roof D whose eaves project outwardly beyond the sides. That portion of the side walls E, comprehended between band C and the roof, rises 20 vertically from band C and curves outwardly to the eaves of the roof. Those portions of the walls F, comprehended between bands B and C, have central outward swells beyond all 25 their margins. Those portions of the walls G, comprehended between bands A and B, have similar central swells. Those portions of the walls H, comprehended between band A and the leg-base L, are ogee in vertical cross-section. The roof D is surmounted by an ornate

mental top piece J of circular convex form. 30 The vertical margins of wall portions F consist of columns K extending between bands B and C. The eaves of roof D, wall portions E, band C, wall portions F, band B, and wall portions G, all have outward swells from the corners of the structure. The base-section of the stove is formed by the portion H and leg-section L jointly. The portion H of the base-section has its vertical contour characterized by reverse curves whose lower convex extremitiess join convex contour-lines of the leg-section, forming at such junction, an angular groove surrounding the base-section at about its mid-height. The ash door M presents itself mainly as a component of the portion H 45 but its lower edge projects below the level of the line N and the door thus carries its individuality into both components of the base-section.

What we claim is—

The design for a heating stove substantially as shown and described.

LAZARD KAHN.
ADAM SPECK.
